BARBECUE PEPPER MILL

Earle G. Hastings, Jr., Tulsa, Okla.

Application August 14, 1953, Serial No. 374,404

2 Claims. (Cl. 241—168)

2

This invention relates generally to devices for applying seasoning and condiments to foodstuffs, and more particularly to mills such as are used to crush or grind pepper and like material.

Conventional condiment mills are awkward to use when cooking over an open fire, in an oven, or even on the back burner of a stove with all the burners being used, without encountering the danger of burning one's self. This is especially true because they require two hands for their operation, one to hold the stationary body or barrel of the mill, and the other to rotate the grinding or crushing means.

In general, it is an object of the present invention to provide a seasoning device of the above character which can be readily and conveniently operated under the above mentioned conditions.

Another object of this invention is to provide a condiment mill having an extended handle and operating means to facilitate its use over open fires and the like.

A further object of the invention is to provide a seasoning device of this kind with an interchangeable top whereby one of the tops adapts the seasoning device for table use, and the other for applying seasoning during cooking.

Other objects and advantages of the invention will appear from the following description taken in conjunction with the accompanying drawing.

Referring to the drawing:

Figure 1 is an elevational view, partly in cross section of my seasoning device.

Figure 2 is a top plan view of the device shown in Figure 1.

Figure 3 is an elevational view, partly in cross section, of a modification of my device.

In general, the present invention consists of a rotary condiment mill to which extended handle and drive means have been applied to facilitate the application of seasoning.

The embodiment of my device shown in the drawing consists of a body or barrel 10 which forms a mounting for the grinding assembly and its operating means.

Any suitable grinding assembly may be used and one found to be satisfactory consists of a grinding cone 11 which coats with a grinding ring 12 mounted in the bore 13 in the lower portion of the barrel 10. A perforated member 14 is attached to the barrel 10 by suitable means such as screws 21 and retains the grinding cone 11 within the grinding ring 12. A chamber 17 adapted to contain seasoning is provided within the barrel 10 and is located above the grinding assembly. A square shaft 18 is attached to the grinding cone 11 and extends axially of the barrel 10 through the chamber 17.

The operating means for the grinding assembly is attached to the upper portion of the shaft 18 and includes a miter gear 19 slidably mounted on the square shaft 18, and a second miter gear 21 engaging the first gear 19.

Any suitable means can be used for supporting the miter gear 19. One supporting means found to be sat-

isfactory consists of a base plate 22 which has a counterbored portion 23 adapted to hold the miter gear 19. The base plate 22, which is permanently pressed into the top shell 41, is detachably secured to a retaining ring 24 as by means of a threaded connection 26. The retaining ring 24 is recessed in the upper portion of the barrel 10 and can be attached to the barrel 10 by any suitable means such as pins 27. This construction allows the barrel assembly to be removed from the top and handle 10 assembly without disturbing or disengaging the miter gears 19 and 21.

The second miter gear 21 may be driven by any suitable extended drive assembly. One assembly found to be satisfactory consists of a shaft 31 extending laterally from the shaft 18. One end of the shaft 31 is fixed to miter gear 21 and the other end is provided with a suitable operating device, such as a knob 32. This knob is shown mounted on the shaft 31 by a knob seating bushing 33 and nut 34.

A suitable housing for the operating assembly is secured to the base plate 22. The housing consists of a cap 41 which is fixed to the base plate 22. A member 42 forms an extended handle and preferably is in the form of a tube which encloses the shaft 31. One end of this tube is secured to the cap 41 as by means of the threaded connection 43. The shaft 31 is suitably journaled in the tubular member 42 as by means of bushings 44.

If desired, a cap nut 46 may be provided for adjusting the position of the grinding cone 11 with respect to the grinding ring 12 to determine the coarseness or the fineness of the grind. The cap nut 46 is threaded on the upper portion of the shaft 17 and engages the cap 41 to raise or lower the grinding cone.

Operation of the device may be briefly described as follows: Let it be assumed that the device has been filled by removing the cap assembly and filling the chamber 17 with a condiment such as pepper corns 47. The grinding assembly is then placed over the foodstuffs to be seasoned and the corns are ground by turning the knob 32. The coarseness or the fineness of the grind can be adjusted by loosening or tightening the cap nut 46.

It will be apparent that this device can be used with the hands in a remote position where they are not subjected to uncomfortable or dangerous heating.

I have added to the utility of my device by providing an interchangeable cap assembly whereby the device can be converted for table use. The cap assembly for table use is shown in Figure 3 attached to the grinding assembly shown in Figure 1. This cap assembly is comprised of a cap 52 which is the same physical size as the cap used for the assembly shown in Figure 1. A base plate 53 with a hub 54 is pressed into the cap 52. The hub diameter is such that it will fit loosely within the threads in the retaining ring 24 so as not to damage them. A square hole 56 is provided in the base plate 53 for passage of the shaft 18. Cap nut 46 holds the cap assembly onto the barrel 10 and also provides a means for varying the size of the grind.

Operation of the device is substantially similar to the operation of the device shown in Figure 1. The grinding assembly is operated by turning the cap assembly itself as rotary motion is imparted to shaft 18 by the square hole 56 in base plate 53. The size of the grind is varied by tightening or loosening the cap nut 46.

The cap assemblies for table use and for barbecue use are made to be interchangeable and therefore the same grinding assembly may be used for either purpose. Changing from barbecue use to table use is a simple operation. Referring to Figure 1, the cap nut 46 is first removed, then the threaded connection 26 is unscrewed by rotating the cap assembly which allows the cap assembly

to be lifted from the barrel and off the shaft 18. The miter gears 19 and 21 still remain in their respective positions even though the miter gear 19 has been disassociated from the shaft 18 because miter gear 19 is recessed in counterbored portion 23 and held there by miter gear 21. This assembly allows the cap assembly for barbecue use to be easily removed from the grinding assembly. Normally in a miter gear assembly, the miter gear 19 would be locked to the shaft 18 which would make removal difficult.

After the cap assembly for barbecue use has been removed, the cap assembly for table use is placed on the square shaft 18 and the cap nut 46 is replaced. The mill is then ready for operation. To convert from table use to barbecue use, the procedure is reversed.

It will be apparent from the foregoing that I have provided a seasoning device which can be used when cooking over an open fire and the like. The device can also be used at the table merely by interchanging cap assemblies.

I claim:

1. In a seasoning device, a barrel, a bore in the lower portion of said barrel, a grinding ring mounted in said bore, a grinding cone rotatably mounted within said grinding ring, a shaft fixed to said grinding cone and extending axially of the barrel, a retaining ring mounted on the upper portion of said barrel, a base plate threadably

mounted on said retaining ring, a miter gear journalled in said base plate and splined on said shaft, a miter gear meshing with said first named miter gear, a cap mounted on said base plate and enclosing said gears, a tubular elongate member mounted on said cap and extending laterally for a substantial distance from said barrel, a shaft journalled in said tubular member and having one end connected to said second named miter gear, and operating means connected to the remote end of said second named shaft for rotating the same.

2. A device as in claim 1 together with means for adjusting the first named shaft longitudinally of the barrel to vary the size of the grind.
